UNITED STATES PATENT OFFICE.

KARL F. JENSEN, OF SOUTH RIVER, NEW JERSEY, ASSIGNOR TO HERMANN AUKAM & CO., OF NEW YORK, N. Y., A CORPORATION OF NEW YORK.

MACHINE FOR USE IN APPLYING CLAMPS TO STRIPS OF FABRIC.

1,154,249.

Specification of Letters Patent. Patented Sept. 21, 1915.

Application filed October 22, 1913. Serial No. 796,719.

To all whom it may concern:

Be it known that I, KARL F. JENSEN, a subject of the King of Sweden, and a resident of South River, in the county of Middlesex and State of New Jersey, have invented certain new and useful Improvements in Machines for Use in Applying Clamps to Strips of Fabric, of which the following is a specification.

10 My invention relates to machines for use in applying to strips of fabrics clamps used for holding such strips in spanning frames.

The machine herein shown and described is particularly adapted for use in applying the clamps employed in the spanning frame illustrated and described in my companion application for Letters Patent filed October 22, 1913, Serial No. 796,718. In the embroidery of handkerchiefs and the like in 20 large numbers, it is the custom to mount a considerable number of handkerchiefs in a suitable frame, termed a "spanning frame," the frame, with the "spanned" handkerchiefs within it, being then placed in a suitable embroidery machine, and then, by the operation of such machine, a like ornamental figure or other device is stitched upon each of the handkerchiefs or other article in such frame, simultaneously. In 25 the use of the spanning frame of my said companion application, the handkerchiefs, preparatory to being placed in the frame, are connected end to end by suitable clamps, these clamps being adapted to fit in suitable

30 seats formed in the frame and to be held in place in the frame by suitable fastening means. Each such clamp comprises two parallel clamping strips between which an end of one handkerchief or two ends of ad-

35 jacent handkerchiefs are to be gripped, and a cover piece of approximately inverted U-form arranged to fit over such clamping strips and to hold them together and also to grip the fabric between its inner surfaces 40 and the outer surfaces of such clamping strips. The machine herein described facilitates the bringing together of such clamping strips, and the application of cover pieces, making it possible to apply the 45 clamps to handkerchiefs very rapidly.

50 My invention consists in the features of the novel mechanism for the purpose specified, herein illustrated and described, which are set forth in the appended claims.

55 The object of my invention is to facili-

tate the application of spanning frame clamps to handkerchiefs and other objects to be spanned.

I will now proceed to describe my invention with reference to the accompanying 60 drawings, and will then point out the novel features in claims.

In said drawings: Figure 1 shows a front elevation and Fig. 2 a side elevation of one form of machine embodying my invention. 65 Fig. 3 shows a fragmentary vertical section on the line V—V of Fig. 1, and on a larger scale. Fig. 4 is a detail sectional view taken on the same section line as Fig. 3, but showing two clamping strips brought together with two strips of fabric fastened between them, and a clamp cover applied. Fig. 5 is a fragmentary bottom view of the machine shown in Figs. 1-4 inclusive, and on a larger scale than Figs. 1 and 2. Fig. 6 70 shows a top view of the table and associated parts of the machine shown in the previous views. Fig. 7 is a perspective elevation of a pair of spanning frame clamping strips such as are to be applied to fabric in the 75 machine illustrated in the previous views. Fig. 8 is an elevation of one of the clamp covers of the spanning frame clamping devices. Fig. 9 is a diagrammatic perspective view illustrating the manner of connection 80 of strips of fabric by clamps such as those which are applied to the fabric by use of the machine illustrated in Figs. 1-5 inclusive. Fig. 10 is a detail sectional view of a 85 portion of a spanning frame with the clamping devices hereinbefore referred to in place therein.

In the drawings, 10 designates a table of suitable dimensions and suitably supported. In the top of this table are slots 11 through 95 which project opposing dogs 12 and 13. The dogs 13 are pivotally mounted upon a slide 14 arranged to move said dogs 13 toward and from the dogs 12; such movement being effected by engagement of rocker arms 100 15 with rods 14^a projecting from the slide 14, and which also guide and support the slide 14, since the rods 14^a pass through suitable sliding bearings in members 10^a and 10^b of the frame. The rocker arms 15 are 105 mounted upon a rock shaft 15^a connected by a lever 16 and link 17 to a foot treadle 18. When this foot treadle is depressed the dogs 13 are moved toward the dogs 12 against the action of springs 19 and 19^a; and when the 110

treadle is released these springs retract the slides 14 and dogs 13.

Numerals 7 designate clamping strips of a spanning frame clamping device. In the 5 construction shown, these strips 7 (usually of metal) are provided at their ends and at certain intermediate points with flanges 9, one function of which is to facilitate holding of the strips 7 by the dogs 12 and 13.

10 In the application of clamping devices to strips of fabric, in the machine forming the subject matter of the present description, one of the clamping strips 7 is placed against the dogs 12 with its flanges 9 beneath the teeth 20 of said dogs 12; another clamping member 7 is placed against the dogs 13 with its flanges 9 beneath the teeth 20 of said dogs 13; edge portions of two pieces of fabric are placed, one against the face of 20 one of the clamping members 7, the other against the face of the other clamping member 7, and then by the operation of the treadle 18 the two clamping members are pushed together; whereupon a clamp cover 21 (Fig. 8) is placed over the clamping member 7, as indicated particularly in Fig. 4. These clamp covers 21 are of approximate inverted U-section, with outwardly projecting flanges 22 at the base, and are of 25 resilient material. In pressing these clamp covers 21 down over the clamping strips 7 the sides of the members 21 are sprung apart somewhat, said clamp covers therefore acting by spring action to hold the 30 clamping strips 7 tightly together and to hold the fabric tightly between them. The tight holding of the fabric is further facilitated by the fact that each strip of fabric passes down between the outside of the corresponding clamping strips 7 and inside of the clamp cover 21 and over one of the base flanges 22 of the clamp cover 21.

The dogs 12 and 13 are pivoted to their supports and springs 23 and 24 permit said 45 dogs to yield as the flanges 22 of the clamp cover 21 are pressed downward, the dogs being forced by the springs 23 and 24 over the edges of such flanges 22, after said flanges have passed the teeth of the said dogs.

50 In applying clamps to a number of strips of fabric to be spanned, the first strip, designated in Fig. 9 by reference letter A, is clamped by itself, along one edge, between the first pair of clamping members 7. The 55 second edge of the strip A and the first edge of the next strip, B, are then clamped together between the second pair of clamping strips 7; and so on.

In Fig. 10 I have illustrated a portion 1 60 of a spanning frame, provided with seats 6 for the clamps 7—21 and with intermediate

clamping devices 5—21. The clamping strips 5 of Fig. 10 are fixed portions of the spanning frame. Since the structure of the 65 spanning frame forms no portion of the present invention I deem it unnecessary to further describe the said spanning frame.

What I claim is:—

1. Clamp applying apparatus comprising a support for clamp-strips, two independent clamp-strip-gripping means, one such gripping means arranged to hold one clamp strip, the other such gripping means arranged to hold another clamp strip, one such gripping means movable toward and from the other and arranged in its movement toward such other gripping means to carry a clamp strip held by it toward a clamp strip held by such other gripping means, and operating means for such movable gripping means. 70

2. Clamp applying apparatus comprising a support for clamp strips, clamp-holding dogs projecting through openings in such support and arranged in pairs, one dog of each pair being movable toward and from the other dog of that pair, and a movable support to which each of such movable dogs is secured, and means for moving said movable support, whereby the movable dogs 85 may be moved toward and from the other dogs. 90

3. Clamp applying apparatus comprising a support for clamp strips, spring-actuated clamp-holding dogs projecting through 95 openings in such support and arranged in pairs, one dog of each pair being movable toward and from the other dog of that pair and a movable support to which each of such movable dogs is secured and means for moving said movable support whereby the movable dogs may be moved toward and from the other dogs, each of such dogs having an inclined upper face and adapted to yield 100 when downward pressure is exerted against such face, and then to spring forward when such pressure is released. 105

4. Clamp applying means comprising a table, a slide mounted to move beneath such table, pivoted spring-actuated dogs mounted on such slide and projecting through 110 openings in said table, other spring-actuated dogs secured to said table and likewise projecting through openings thereof, and means for operating said slide. 115

In testimony whereof I have signed this specification in the presence of two subscribing witnesses.

KARL F. JENSEN.
